US00D941721S

(12) United States Design Patent (10) Patent No.: US D941,721 S
(45) Date of Patent: * Jan. 25, 2022

(54) VEHICLE FLOOR MAT

- (71) Applicant: HYUNDAI MOBIS CO., LTD., Seoul (KR)
- (72) Inventor: Hyun Jin Chang, Yongin-si (KR)
- (73) Assignee: HYUNDAI MOBIS CO., LTD., Seoul (KR)

() Term: 15 Years

(21) Appl. No.: 29/796,283

(22) Filed: Jun. 23, 2021

Related U.S. Application Data

- (62) Division of application No. 29/708,255, filed on Oct. 4, 2019, now Pat. No. Des. 929,284.
